(57) **CLAIM**

We claim the ornamental design for a combined chopsticks and stand, substantially as shown and described.

DESCRIPTION

FIG. 1 is a perspective view of a combined chopsticks and stand, in accordance with the present design.

FIG. 2 is a front view of thereof.

FIG. 3 is a back view of thereof.

FIG. 4 is a top view thereof.

FIG. 5 is a bottom view thereof.

FIG. 6 is a left side view thereof.

FIG. 7 is a right side view thereof; and,

FIG. 8 is an exploded perspective view thereof.

The broken lines in the figures illustrate the portions of the design that form no part of the claimed design.

The dot-dot-dash broken lines immediately adjacent to the claimed areas in the views represent the boundaries of the design and form no part thereof.

None of the broken lines form any part of the claimed design.
